UNITED STATES PATENT OFFICE.

OTTO J. GROEHN, OF DETROIT, MICHIGAN, ASSIGNOR TO CLAYTON & LAMBERT MANUFACTURING COMPANY, OF DETROIT, MICHIGAN, A CORPORATION OF MICHIGAN.

TORCH BURNER.

1,420,696.

Specification of Letters Patent. Patented June 27, 1922.

Application filed February 14, 1921. Serial No. 444,727.

To all whom it may concern:

Be it known that I, OTTO J. GROEHN, a citizen of the United States of America, residing at Detroit, in the county of Wayne 5 and State of Michigan, have invented certain new and useful Improvements in Torch Burners, of which the following is a specification, reference being had therein to the accompanying drawings.

10 This invention relates to torch burners and refers more particularly to a new and improved construction of blow torch. In blow torches such as used by plumbers, metal workers and the like difficulty is encountered 15 in starting and preventing the blowing out or interruption of the flame, particularly in the larger sizes of torches. Owing to the large amount of surface to be initially heated it often takes considerable time to 20 start the torch and one of the objects of the present invention is to provide a torch which can be quickly and easily started; to provide a torch or burner therefor which can be cheaply constructed and in which the 25 fuel is vaporized at a point near the discharge orifice thus preventing the condensing of the vaporized fuel; to provide a construction wherein a relatively small drip cup can be employed for starting and to 30 so construct and arrange the parts that a smaller blow torch which can be easily started is employed for preheating or vaporizing the fuel to be burned in the main or larger nozzle. The invention also resides in the 35 novel arrangement of the vaporizing coil and in such further features of construction and arrangements and combinations of parts and operations as will more fully hereinafter appear.

40 In the drawings:

Figure 1 is a vertical longitudinal section through a torch burner embodying my invention; and

45 Figure 2 is a cross-section on the line 2—2 of Figure 1.

Describing in detail the particular embodiment of my invention shown in the drawings, A designates a torch burner having a shell B which is provided at its forward end with an enlarged burner chamber B'. The latter may or may not be provided with an additional extension B² thus permitting the various sections of the combustion chamber to be economically manufac-

tured and assembled. Near its forward end 55 the casing B is provided with a coil C which at its forward end terminates in a nozzle portion C' having the removable discharge nozzle C² in which the main discharge opening C³ is located.

60 At its rear portion the casing B is provided with a supplemental torch burner D which is preferably a complete smaller blow torch having the combustion chamber D', the control valve D², the preheating valve or passageway D³ connecting through the hollow stem D⁴ to the main fuel supply pipe E. The latter is controlled by a main valve E' and the supplemental torch burner D 65 preferably has the usual drip cup F. Between the plane hollow stem D⁴ and that of the upright portion of the coil C there is preferably located a second control valve G which governs the communication between the main fuel supply pipe E and the coil C. 70 The casing B is preferably carried by uprights H and H' mounted by suitable fittings on the main fuel supply pipe E. Thus when the torch is assembled they form a 75 complete unit, the operation of which is as follows: In place of attempting to heat and vaporize the large quantity of fuel necessary for the main burner C² it is only necessary to vaporize the amount of fuel employed for the supplemental burner nozzle J of the supplemental torch burner D. This can be done 80 by a small amount of liquid fuel in the drip cup F so as to initially heat the parts. The main supply valve E' being opened the liquid fuel under pressure will pass up through 85 the stem D⁴ preheating the passageway D³ and being burned at the supplemental orifice J' the needle valve D² being adjusted to govern the amount of opening through the nozzle J. This will develop the ordinary hot 90 flame in the combustion chamber D', the flame being projected to the outward end of the combustion chamber D' which is in substantially axial alignment with the coil C. Thus an extremely hot flame is thrown 95 not only on the coil C but also on the rear portion of the main discharge nozzle C'. As soon as these parts are heated to the proper temperature the valve G is opened 100 allowing the fuel to be vaporized in the cup coil C. Then without having any chance to cool and condense it is passed to the hot main nozzle C² out of which it is forced un-

der pressure and burned within the main combustion chamber D'. This novel construction not only permits of the easy starting of the torch burner but it insures the burner continuing in operation as the degree of heating on the vaporizing coil can at all times be controlled by the adjustments of the valve D². While I have shown and described the use of a smaller blow torch for use in heating the coil in certain aspects of the invention this feature is important but the invention in its broader aspects is not limited to the use of such a burner for pre-heating the coil nor to other features of construction and combinations of parts except as ultimately set forth in the claims.

What I claim as my invention is:

1. In a burner for torches or the like, the combination with a casing a combustion chamber located at one end of said casing, a main fuel nozzle in said combustion chamber, a coil for supplying fuel to said nozzle located in the rear of said nozzle and a supplemental burner for heating said coil and means dependent of said coil for supplying a fuel to said main fuel nozzle.
2. In a burner for torches or the like, the combination with a casing a combustion chamber located at one end of said casing, a main fuel nozzle in said combustion chamber, a coil for supplying fuel to said nozzle located in the rear of said nozzle and a supplemental burner for heating said coil, said supplemental burner having its combus-

tion chamber substantially in axial alignment with said coil.

3. In a burner for torches or the like, the combination with a casing, of a main burner nozzle located in the casing, valve controlled means for supplying a fuel to said nozzle, a vaporizing chamber located in the casing, a supplemental nozzle in the rear of the first named nozzle for heating said vaporizing chamber, and independent valve controlled means for supplying a fuel to the last mentioned nozzle.

4. In a burner for torches or the like, the combination with a casing, of a main burner nozzle located in the casing, a coil connected to said nozzle, valve controlled means for supplying a fuel to said coil, a supplemental nozzle in rear of the first named nozzle for heating said coil, and independent valve controlled means for supplying a fuel to the last mentioned nozzle.

5. In a burner for torches or the like, the combination with a casing, of a main burner nozzle located in said casing, valve controlled means for supplying a fuel to said nozzle, a vaporizing chamber also located in the casing, a supplemental nozzle in the rear of said vaporizing chamber, and means for supplying a fuel to the supplemental nozzle, said supply means being spaced from and independent of the supply means aforesaid.

In testimony whereof I affix my signature.

OTTO J. GROEHN.
